UNITED STATES PATENT OFFICE

EMILE GUINOT, OF PARIS, FRANCE

PROTECTING APPARATUS FOR PRESSES AND THE LIKE

Application filed April 19, 1927, Serial No. 185,006, and in France April 19, 1926.

Numerous apparatuses are already known for protecting the hands during operation on presses, machine-tools and the like, but these apparatuses, whether they comprise a shutter with a hand guard, or whether they are based on a clutch actuated with both hands, are either of a very little protection, or of such a construction that it is difficult to adopt them on the different types of machines, or again 10 they considerably hinder the work of the operator and thus diminish the production.

The same is true for apparatus comprising a rocking shield coming in front of the tool as the pedal operates the said shield, 15 as it often happens that the workman, to gain time, withdraws his foot from the pedal immediately after he has thrown the machine in gear. In this case, the shield is withdrawn before the punch has effected its 20 operation.

On the other hand, a safety device automatically throwing the machine out of gear after each stroke, when the foot would be pressing on the pedal, is not efficient and 25 must, for protecting the workmen's hands, be completed by a special protecting apparatus.

Finally, when the protector is positively connected to the pedal, the rapid descent of 30 the protector can inflict injury to the workman according to the energy of the pressure of the foot on the pedal.

The present invention is adapted to do away with or attenuate the above mentioned 35 inconveniences and has for an object a protecting apparatus for presses, machine tools and the like, in which the throwing in gear cannot take place until the fingers of the workman are outside the vicinity of the tool 40 or out of reach of the dangerous movable parts.

In the apparatus hereinafter described, the 45 protecting shield descends rapidly by its own weight (the joint being perfectly oiled), which movement cannot harm the workman, and the apparatus is provided with a safety device, so that the protecting shield protects the workman for the entire duration 50 of the work operation of the machine, as it is only at the end of the stroke that the

apparatus can return to its initial position.

The apparatus forming the subject-matter of the present invention is constituted principally by: a rocking control lever having a return spring, one arm of the said lever having an adjustable abutment screw and the other arm being terminated by a finger forming a stop piece; a rocking cam provided with a stop tooth and an abutment arm, the said cam being controlled by the 55 said lever or wedging it to ensure protection and both of which are enclosed in a box arranged in a suitable place on the frame; one or two levers fixed outside the box on the axis of the cam and carrying rods adjustable with the protecting shield; a double lever fixed on the axis of the control lever and connected on one side to the locking clutch member of the machine by a link having 60 an oblong opening or lost motion slide and, on the other side, by a rod adjustable in position by the control of the clutch; and if necessary a safety device locking the protecting apparatus when the shield has moved 65 down to the full extent of its stroke and releasing the said apparatus by taking the control on the dangerous movable part of the machine when the protecting shield can be raised without any danger for the workman's hands. 70

The invention is described hereinafter in detail with reference to the accompanying drawing which shows by way of example two forms of construction of the protecting 75 apparatus, with supplementary safety device, constructed according to the principle specified and applied to a press.

Fig. 1 illustrates in elevation, the protecting apparatus, with the cover enclosing the 80 control lever and the cam, removed, and also showing the safety device.

Fig. 2 is a plan view of the apparatus illustrated in Fig. 1.

Fig. 3 is a cross sectional view of a part 85 of the apparatus shown in Fig. 1.

Fig. 4 is an elevation of the box without the lid and without the safety device.

Fig. 5 is an elevation of the box without 90 the lid, but with the inner parts in position 100

when the machine is thrown in gear and with the safety device in action.

Fig. 6 shows corresponding positions of the rocking control lever and of the driven 5 cam permitting the operation of the machine.

Fig. 7 shows the corresponding position of the same parts when the hands or any other obstacle prevent the protecting shield from moving down to the entire extent of its 10 movement and thus preventing the throwing in gear and the operation of the machine.

Fig. 8 is a side elevation of the modification of the apparatus.

Fig. 9 shows the arrangement of the cams 15 within the box.

Fig. 10 is a plan view of the apparatus shown in Fig. 8.

Fig. 11 shows a press, partly in section, provided with a supplementary safety device 20 fitting on the protecting apparatus, particularly for slow-running presses.

In the drawing, 1 indicates the box secured in a suitable place on the machine by lugs 2 and closed by a lid 3 and screws 4.

25 On an axis 5, which is journalled and rocks in the box and the lid, is secured a control lever 6, an arm of which, slotted at 7 for the passage of the clamping screw 8, carries an adjustable abutment 9, and the other arm 30 of which is terminated by a finger 10 forming a stop piece, the said lever being constantly subjected to the action of a returning spring 11 secured at 12 to the box and at 13 to a pin on the lever.

35 On another axis 14, also rocking in the box and the lid, is secured a cam 15 having a stop tooth 16 with a notch and an abutment arm 17, the said cam being in relation with and controlled by the lever 6 by which it is 40 locked, in case of an obstacle preventing the protecting shield from moving down to the full extent of its stroke.

On the axis 14, which extends through the lid 3 there is secured, by a cone for regulating its orientation, a lever 18 with cone 45 bearings therebetween to permit varying their relative position with a rod 19 adjustably positioned as at 20 and carrying a protecting shield 21, perforated for permitting 50 observation of the tool.

The axis 14 can be connected, across the frame, by an extension in the shape of a tube 22, to another stub shaft 23 journalled in a support 24 secured to the frame 25 of the machine.

55 This stub shaft 23 is provided with a lever 26 having a rod 27 adjustably positioned as at 28 for supporting on the other side the protecting shield 21.

It is obvious that the axis 14 need not be extended and the protecting shield 21 can be held by one lever 18 alone.

60 The protecting shield by its own weight, tends to descend and to cause the arm 17 to

follow the abutment 9 of the lever 6 to keep itself in contact with the latter.

The rocking of the levers 18 and 26 is regulated so that the protecting shield 21 is stopped in its downward movement and by 70 means hereinafter described prevents the throwing into gear of the machine when the workman's hand are still in the danger zone of the tool or in the vicinity of the movable parts. The movement of the levers 18 and 75 26, either by abutments 29 30 or by abutments secured on the tool, which stop the shield, or in any other suitable manner and they are adjustably secured on the axis 14 so that, at the lower position of the shield, 80 the tooth 16 of the cam 15 disengages the nose or finger 10 of the lever 6 so as to permit the latter to continue its stroke.

On the axis 5 and in front of the lid 3 is secured, also by a conical part, a double lever 85 31, the upper eye 32 of which is connected to the clutch locking members of the machine by a link 33 having an oblong opening 34, whilst the lower eye 35 is connected to the starting control, handle or pedal, by a rod 36 adjustable in position by a screw 37.

The length of the oblong opening will be determined according to the rocking of the shield and the idle stroke of the link is taken on the stroke of the pedal and so to speak 95 without effort.

The box 1 carries a boss 38 in which moves a locking rod or safety bolt 39 constantly pressed, by a spring 40 of a housing 41, against the lever 6 provided with a notch 42 to receive the said safety bolt 39 and to thus lock the apparatus.

The locking rod 39 is terminated by a stop 43 in contact with the arm 44 of the bell crank lever, rocking on the axis 45 of a support 46 100 projecting from the box 1.

The second arm 47 of the bell crank lever carries an adjustable extension 48 with an abutment 49 also adjustable, capable of placing itself under the slide or any other part 110 or extension of the slide-block 50 of a press or under the dangerous movable part of a machine.

The operation of the machine is as follows:

When the machine is at rest, the parts occupy the positions illustrated in Figs. 1, 2, 3 and 4, that is to say the protecting shield 21 is in its uppermost position and clears the tool, the lever 18 rests against the abutment 29 and the returning spring 11 acting on the lever 6, raises the double lever 31 and maintains the contact of the abutment 9 with the arms 17.

As soon as the starting rod 36 is operated, by drawing it downwardly, the axis 5 rocks under the action of the returning spring 11, the double lever 31, moves down, drawing with it the link 33, whilst the arm of the lever 6 carrying the abutment 9 rises and releases the arm 17 of the cam 15.

The protecting shield 21, acting by its own weight causes the axis 14 to rock and, with it, the released cam, so that its arm 17 rises for remaining in contact with the abutment 9 of 5 the lever 6.

If the protecting shield 21 falls completely until it reaches its lowermost position, that is to say that no part whatever or hands are in the dangerous zone or in the vicinity of 10 the tool, it is from this moment only that the actuation of the clutch can begin to take place.

The throwing in gear commences at the precise moment the lever 6 and cam 15 reach 15 the position shown in Fig. 6, that is to say, that the nose 10 of the lever 6 passes beyond the tooth 16 and can become engaged into the notch of the cam 15.

At this moment and during the actuation 20 of the clutch, the lever 6 continues its rocking movement and the cam 15 stopping, the nose 19 enters farther and farther into the notch, so that at the end of the throwing in gear the parts will take the position shown in 25 Fig. 5.

It will be noted that at the very moment the lever 6 and the cam 15 take the position shown in Fig. 5, the safety device will begin to act, that is to say the bolt 39 pressed by 30 the spring 40, will enter the notch 42 of the lever 6 and will lock the protecting apparatus, thus preventing the shield 21 to rise before the slide-block 50 has accomplished its operation or its entire down stroke.

In these conditions, if the slide-block 50, or the dangerous part of the machine stops during the operation, the protecting shield 21 is held down and prevents the workman from placing his hands in the dangerous zone before proceeding to a new actuation of the clutch producing the complete descent of the slide-block.

It will be seen, therefore, that this safety device is particularly useful and efficient in 45 case the workman removes his foot from the pedal too rapidly and that the shield rises before the punch has effected its work, or again, when the slide-block stops during its movement.

In fact, when the slide-block 50 reaches the end of its stroke, it acts, a short time before, on the abutment 49 by lowering the extension 48 with the arm 47 of the bell crank lever, the other arm 44 of which acts on the 55 stop 43, forces the bolt 39 out of the notch 42 against the stress of the spring 40, and releases the lever 6, thus permitting the operation of the protecting shield and the raising of the protecting shield, without danger for 60 the workman's hands.

It is obvious that the latching up of the main control lever 6 can be effected by all other means suitable to the machine and that, in certain cases, especially with high speed 65 machines having a small stroke, the safety

device could be done away with and rendered inoperative as then, during the automatic operation of the machine, the shield usually remains in protecting position and rises only at the time the machine stops.

On the contrary, if the protecting shield does not completely fall to its lowermost position and stops on the way because one hand of the workman is belated and still remains in the dangerous zone, thus preventing the free and complete descent of the said protecting shield, the arm 17 will not follow the abutment 9, the finger 10 of lever 6 will abut against the outer surface of the cam 15 and these members will take the position shown in 70 Fig. 7.

It will be seen that in this latter position, the lever 6 cannot continue to rock and to move downwards in order to be able to actuate the clutch device, the machine will not 85 operate notwithstanding the action on the link 36 controlling the starting of the machine.

We shall now suppose that the apparatus is applied to a pedal press.

When the slide-block has risen and that the starting pedal has been released, the machine stops at the top of its stroke and the protecting shield comes back into its uppermost position, under the action of the returning 95 spring.

In these conditions, three cases can occur:

1.—The press is provided with a safety clutch.

In this case, the slide-block is automatically unclutched at each end of its stroke, even when the pressure on the pedal is maintained.

In these conditions, the pedal must be abandoned and a new pressure must be exerted on this pedal for reclutching and the protecting apparatus then comes back to its starting position.

2.—The press is not provided with a safety clutch.

In this case, as long as the foot presses on the pedal, the press continues to work.

In these conditions, the application of the protecting device does not present any inconvenience, since the shield is always in its lowermost position during the time a pressure is exerted on the pedal and it rises only when the latter is abandoned.

3.—The press can be provided with the safety clutch or with the ordinary clutch.

Let us suppose that the operator immediately removes his foot from the pedal as soon as he has thrown the machine in gear:

In these conditions, with the safety device of the apparatus, the protecting shield remains in position until the tripping action occurs at the end of the stroke which causes the shield to come back to its starting point.

The form of construction of the modified apparatus illustrated in Figs. 8, 9, 10 shows 130

the adjustment devices and various arrangements of the parts for ensuring the protection and for rendering the apparatus more easily applicable to the various machines.

In fact in the improved apparatus hereinafter described, the extreme positions of the cams and, consequently, those of the protecting shield are adjusted from the exterior and the apparatus comprises various adjusting devices to compensate for the variations of the strokes and of the heights of the tools; to this apparatus can be adapted a supplementary device, very useful in certain cases, for increasing the security and efficiency of protection.

In the drawing, the removable shield 21', made of perforated sheet-iron, is secured by screws on a U-shaped rod 19' which is itself secured on two double levers 18' and 20' pivoted on an axis 22' of the box 1' having a cover 3'.

On the frame 25' of the press 51' is secured the box 1' in which are arranged two cams 6' and 15' made of cemented and hardened steel.

The upper cam 6' is mounted on the axis 5' carrying, at the front of the cover, an operating lever 31, the lower cam 15' is mounted on the axis 14' carrying the lever 18'.

The lever 31' is connected, on the one hand, to the pedal by the adjustable rod 36' and, on the other hand, to the clutch control by the rod 33'.

The connection of the rod or link 33' with the lever 31' is not rigid, the rod slides in a yoke 52 and its stroke is adjustable.

The stroke of the protecting shield is limited at the top by the abutment screw 53 and at the bottom by the abutment screw 54.

The latter is usually adjusted during the assemblage whilst the abutment screw 53 can be adjusted according to the press requirements for causing the angle of oscillation of the shield to vary.

The adjustment of both cams 6' and 15' is such that when the cam 15' is in contact with the abutment 54, the nose 10' of the cam 6' can enter without play into the notch formed in the cam 15'.

The spring 55 has no action whatever on the operation of the shield, it is simply adapted to maintain the connection between both cams 6' and 15' and to avoid the shocks which would alter the profile of the latter; the noses 9', 10' and 16' can obviously be adjusted by means of screws or otherwise.

It will be understood that the cams can be replaced by levers provided with holes or notches and abutments, adjustable or not, or by similar means and according to the purpose sought for.

The operation of this device is similar to that previously described.

In the position of rest, the lever 18' of the

cam 15' bears upon the abutment 52, the noses 10' and 16' are completely released and the nose 9' of the cam 6' presses upon the cam 15' for holding the shield 21' in position at the top of its stroke.

As soon as the pedal is pressed upon, the operating lever 31' drives the cam 6', this causing the contact between cam 15' and cam 6' to cease, contact which was maintained by the action of the weight of the shield 21' and of the levers.

When the shield 21' has effected its entire rocking movement, that is to say when the cam 15' is in contact with the abutment 54, the cam 6' can still continue its oscillation and the nose 10' of the cam 6' can enter the notch of the cam 15'.

The abutment nut 56, secured on the link 33' is so adjusted that when the nose 10' of the cam 6' is opposite the nose 16' of cam 15', a slight clearance remains between the nut 56 and the yoke 52.

By continuing to press upon the pedal, the link 33' is moved and the clutching action takes place in the same way as described in the preceding example.

If, accidentally, the shield cannot accomplish its full rocking movement, either because the workman has not removed his hand from the tool, or because any member is engaged on the die, the cam 6' abuts on the circular portion of the cam 15' and thus cannot continue its rocking movement that is to say although the workman presses upon the pedal, the latter remains stationary.

It frequently happens that, for the purpose of gaining time, the workmen operating the presses are accustomed to remove the foot from the pedal as soon as the throwing in gear has taken place; this rapid operation has no inconvenience in the case of presses provided with a flywheel, but might have inconvenience with presses having gears and a long stroke, that is to say slow-running presses.

In fact, as soon as the workman releases the pedal, the protecting apparatus takes back its initial position and the shield rises; then it might happen that the rising of the shield might take place before the slide-block has entirely effected its down stroke.

Thus, for ensuring an absolutely efficient protection in the case of presses provided with eccentrics, gears and having a long stroke, use can be made of the following safety device (see Fig. 11).

A lever 57 is fitted on the axis 22 of the shield-carrying lever, this lever being provided at the front with a rectangular mortice 58 for permitting the passage of a rocking bolt 59 having a stop projection 60; on the other hand, on the slide-block 50 of the press is secured an adjustable abutment 61.

The operation of the apparatus is then as follows:

When the shield 21' arrives at the bottom of its stroke the rocking lever 59 locks the lever 57, so that when the workman releases the pedal before the slide-block 50 has effected its up stroke, the said lever 57 cannot rise and it is only when the slide-block 50 arrives at the end of its stroke that the abutment 61 acts upon lever 59 for releasing the lever 57, and the protecting shield can re-take its up per initial position.

The protecting apparatus modified as above described can be fitted on all types of presses and comprises all the adjusting devices for compensating the variations of 15 strokes and height of tools.

Thus, it can be applied very easily on all eccentric presses.

The protecting shield, instead of being positively actuated during the downward 20 movement by the clutch pedal (which has the inconvenience of hurting the operators) descends by its own weight and the levers on which it is secured are balanced by a counter-weight 62 so that the downward movement 25 should not be too rapid, so that the workman can support the shock of the shield without being inconvenienced.

On the contrary, the rising of the shield is positively ensured by the rising movement of 30 the pedal.

The shield can be very easily adjusted in all the positions; it can be moved towards or from the center of the slide-block, and the angle of oscillation can be adjusted according 35 to the requirements.

The shield can be adjusted for permanently occupying a position for ensuring protection when the tool operates in a continuous manner, as it suffices to adjust the 40 abutment 58 accordingly for obtaining a locking action.

The operation of the apparatus is absolutely safe and takes place without the help of any spring.

45 What I claim as my invention and desire to secure by Letters Patent is:—

1. A protecting apparatus for presses and machine tools having a clutch and a clutch operating pedal, comprising a box mounted 50 on the machine, a shaft having bearings in the walls of said box and projected beyond a side thereof, a rocking operating lever mounted on said shaft within the box, a spring for returning said shaft to a normal 55 position, one arm of said lever being provided with an adjustable abutment and the other arm terminating in a finger, a second shaft having bearings in the walls of said box and projecting beyond the walls thereof, 60 a rocking cam lever mounted on said second shaft within the box having an abutment and a stop tooth, the said levers lying in the same plane, the abutment arm of said levers adapted to engage each other in one operative 65 position, and the finger on the operat-

ing lever adapted to engage the stop tooth of the cam lever in another operative position, the said cam lever being actuated by said operating lever by said spring in one direction, a link secured on the shaft to which the 70 cam lever is secured outside the box, a protecting shield secured to said link, a double lever secured on the shaft to which operating lever is secured and means for connecting one arm of said lever to the clutch of the 75 machine, such connecting means comprising a lost-motion connection, and means for connecting the other arm of said lever to the clutch operating pedal.

2. The protecting apparatus according to 80 claim 1 in which the finger of the operating lever is adapted to engage the tooth of the cam lever to lock the cam lever against return movement until it has completed a full movement in one direction.

3. A protecting device according to claim 1 and in combination therewith of a member 85 adapted to lie in the path of a movable part of the machine and means operated by said operating lever to remove said member from the path of said movable part in a last period 90 of movement of said lever.

4. A protecting device according to claim 1 and in combination therewith of a member 95 adapted to lie in the path of a movable part of the machine and means operated by said operating lever to remove said member from the path of said movable part in a last period of movement of said lever, said means comprising a movable rod and an abutment 100 on said lever normally out of engagement and adapted upon movement of the lever to engage therewith.

In testimony whereof I have signed my name to this specification.
